US0D1006977S

(12) **United States Design Patent** (10) **Patent No.:** **US D1,006,977 S**
(45) **Date of Patent:** **** Dec. 5, 2023**

(54) **AIR DISTRIBUTION BOX**

(71) Applicant: **Dometic Sweden AB**, Solna (SE)
(72) Inventors: **Rickard Hederstierna**, Hägersten (SE);
Samuele Meda, Solna (SE); **Jarrod Williamson**, Victoria (AU); **Jason Svare**, Victoria (AU); **Louis Liu**, Zhuhai (CN)

(73) Assignee: **Dometic Sweden AB**, Solna (SE)

(**) Term: **15 Years**

(21) Appl. No.: **29/774,535**

(22) Filed: **Mar. 17, 2021**

Related U.S. Application Data

(62) Division of application No. 29/660,094, filed on Aug. 17, 2018, now Pat. No. Des. 917,036.

CLAIM

The ornamental design for an air distribution box, as shown and described.

DESCRIPTION

FIG. 1 is a perspective view of an air distribution box design; FIG. 2 is a first side view of the air distribution box design of FIG. 1;

FIG. 3 is a second side view of the air distribution box design of FIG. 1;

FIG. 4 is a third side view of the air distribution box design of FIG. 1;

FIG. 5 is a fourth side view of the air distribution box design of FIG. 1; and,

FIG. 6 is a bottom view of the air distribution box design of FIG. 1.

The broken line disclosure represents unclaimed portions of the air distribution box in which the design is embodied.

1 Claim, 6 Drawing Sheets
